VERTICALLY ADJUSTABLE TABLE

William J. Stanley, Long Beach, Calif.

Application July 19, 1955, Serial No. 522,958

5 Claims. (Cl. 311—39)

The invention herein has relation to a table equipped to be vertically adjustable selectively to situate a top thereof at a relatively high position, as when to be used as a so-called card table, and at a comparatively low position, as when to be used as a so-called coffee table.

The object of the invention is to provide a vertically adjustable table of the present general character which will be of simple, inexpensive, efficient, novel and improved construction.

In the accompanying drawing forming a part of this specification,

Fig. 1 is a perspective view of a table made according to the invention as when adjusted to have maximum height;

Fig. 2 is a side elevational view of the table as when adjusted to have minimum height;

Fig. 3 is a side elevational view corresponding generally with the disclosure of Fig. 2 but showing the table as when adjusted to have maximum height;

Fig. 4 is an enlarged vertical sectional view, taken on line 4—4 in Fig. 3, but showing the table as when the top thereof is at its highest possible elevation;

Fig. 5 is a detail sectional view, taken on line 5—5 in Fig. 2;

Fig. 6 is a view, partially in elevation and partially in section, detailing the manner of detachable assembly of lower and upper half-legs of the table; and

Fig. 7 is a detail sectional view, taken on line 7—7 in Fig. 3.

The new and improved table is constituted as a lower unit, denoted generally at 10, and an upper unit, indicated generally at 11.

The lower unit 10 includes a base member consisting of intersecting horizontal rails 12 in perpendicular relation to each other and supporting feet 13 for the table, there being a supporting foot upon the outer end of each rail 12. The supporting feet 13 are equidistantly spaced from the location where the rails 12 intersect.

Said lower unit also includes lower half-legs 14, there being a lower half-leg rigid with and extending vertically upwardly from each of said supporting feet. An upwardly facing supporting surface 15 of each foot 13 is situated adjacent a side of the lower end of the corresponding lower half-leg 14. Said lower half-legs are disposed at 90 degrees apart, as are also the upwardly facing supporting surfaces 15. The lower half-legs 14 and the upwardly facing supporting surfaces 15 are in a single circumference. There is a lower half-leg between each of adjacent upwardly facing supporting surfaces, and an upwardly facing supporting surface between each of adjacent lower half-legs.

In addition to the base member and the upstanding lower half-legs 14, the lower unit 10 includes a hollow post 16 which extends vertically upwardly from said base member at the location where the horizontal rails 12 intersect. The hollow post 16 is in concentric relation to the circumference in which the lower half-legs 14 and the upwardly facing supporting surfaces 15 lie,

2

and said hollow post can be secured upon the base member in any suitable and convenient manner, as represented generally at 17. A plate member 18, fixedly supported, as at 19, upon the lower end of the hollow post 16 at a location below the elevation of the horizontal rails 12, itself fixedly supports, as at 20, a guide rod or element 21 which extends upwardly through said hollow post in spaced, concentric relation to its cylindrical internal surface 22. As disclosed, the upper end portion of said cylindrical internal surface is of reduced diameter and is lined by a hollow tubular fitting 23 having an exteriorly flared lower end portion 24 fitted against a converging surface 25 of the cylindrical internal surface 22. As shown, a flange upon the upper end of the hollow tubular fitting 23 is fastened down, as at 26, against the upper end of the hollow post 16.

The upper unit 11 includes a table top, of rectilinear configuration as disclosed, consisting of a flat horizontal element 27 with a sheet covering 28 upon the upper surface and a depending skirt 29 at each of the sides thereof.

Said upper unit also includes upper half-legs 30, there being an upper half-leg rigid with and extending vertically downwardly from each of the four corners of the table top. Said upper half-legs are disposed at 90 degrees apart, and when the lower and upper units 10 and 11 of the table are in assembled relation, the upper half-legs 30 will lie in a single circumference with the lower half-legs 14 and the upwardly facing supporting surfaces 15. Also, each of adjacent upper half-legs 30 are spaced 30 apart the same distance as are each of adjacent lower half-legs 14 and upwardly facing supporting surfaces 15, respectively. And, too, all of the upper and lower half-legs 14 and 30 are of equal length.

In addition to the table top and the downwardly extending upper half-legs 30, the upper unit 11 includes a hollow tubular element 31 which extends vertically downwardly from said table top at the center thereof. The hollow tubular element 31 is in concentric relation to the circumference in which the lower half-legs 14, the upwardly facing supporting surfaces 15 and the upper half-legs 30 lie when the lower and upper units 10 and 11 are assembled, and said hollow tubular element can be secured to the table top in any suitable and convenient manner. As shown, a threaded end cap 32, secured, as at 33, upon the upper end portion of the hollow tubular element, is fastened, by screws 34, up against the lower surface of the flat horizontal element 27 of the table top. A cup shaped central portion 35 of said threaded end cap is situated in a centrally disposed cavity in said flat horizontal element. The lower portion of said hollow tubular element is snugly vertically slidable, as at 36, in the hollow tubular fitting 23 and an exteriorly flared lower end portion 37 of the hollow tubular element is engageable with the internal surface of the exteriorly flared lower end portion 24 of the hollow tubular fitting 23 thus to preclude removal of said hollow tubular element from said hollow post. A cylindrical internal surface 38 of the hollow tubular element 31 is in spaced relation to the guide rod or element 21 and a compression coil spring 39, within the hollow post 16 and the hollow tubular element 31, upon said guide rod or element and seated between the plate member 18 and the central portion 35 of the end cap 32, is for counterbalancing a major portion of the weight of the table top.

A manually manipulable set screw 40 in the side wall of the hollow post 16 is capable of engagement with an external surface of the hollow tubular element 31 to preclude vertical movement of the table top relative to the base member.

The lower surface of the flat horizontal element 27 of the table top is provided with sockets 41, there being a socket 41 adjacent a side of each upper half-leg 30,

and each lower half-leg 14 has a protuberance 42 upon its upper end for entrance into a corresponding socket 41. The sockets 41 are spaced at the same distance apart as are the upper half-legs 30. The lower end of each upper half-leg 30 is provided with a socket 43 for receiving a protuberance 42 upon a corresponding lower half-leg 14.

In Figs. 1 and 3 of the drawing, the table is shown as when adjusted to the relatively high position for the table top to serve as a card table. The lower and upper half-legs 14 and 30 are in vertical alinement and the protuberances 42 are situated in the sockets 43. That is, the lower and upper half-legs 14, 30 at each of the four corners of the table top when in relatively high adjusted position serve as full length legs which are twice as long as are each of the lower and upper half-legs. In Figs. 2 and 5, the table is shown as when adjusted to the comparatively low position for the table top to serve as a coffee table. The lower and upper legs are in horizontal alinement, the protuberances 42 are in the sockets 41 and the lower ends of the upper half-legs 30 are rested upon the upwardly facing supporting surfaces 15. The table top is adjustable from its position as in Figs. 1 and 3 to its position as in Figs. 2 and 5 merely by elevating the upper unit 11 until the upper half-legs 30 are clear of the protuberances 42, rotating the table top until the sockets 41 are vertically alined with the lower half-legs 14 and the upper half-legs 30 are vertically alined with the upwardly facing supporting surfaces 15, and lowering said upper unit until said protuberances 42 enter the sockets 41 and the lower ends of said upper half-legs rest upon said upwardly facing supporting surfaces. Said table top is adjustable from its position as in said Figs. 2 and 5 to its position as in said Figs. 1 and 3 in response to manipulations which are the reverse of those required to adjust the table top from its position as when serving as a card table to its position as when serving as a coffee table. When the table is set up as a card table, rotation of the upper unit 11 relative to the lower unit 10 will be precluded by reason of engagement of the protuberances 42 in the sockets 43, and when the table is set up as a coffee table, rotation of said upper unit relative to said lower unit will be precluded by reason of engagement of said protuberances 42 in the sockets 41.

It is to be understood that the disclosure herein is merely illustrative of the invention and meant in no way, in a limiting sense. By way of example, the table top could be of shape other than rectilinear, and the base member could be of construction considerably different from that illustrated and described.

What is claimed is:

1. A vertically adjustable table comprising a base member, a vertical post extending upwardly from said base member, spaced, lower part-legs upon the base member, a table top, a vertical element extending downwardly from said table top assembled with said vertical post for rotative and sliding movement, and spaced, upper part-legs extending downwardly from the table top, said lower and upper part-legs being situated in a circumference concentric with said vertical post and vertical element, there being a lower part-leg corresponding to each of said upper part-legs, and said table top being rotatably and slidably adjustable selectively to situate lower ends of said upper part-legs in engaged relation with upper ends of their corresponding lower part-legs or to situate corresponding lower and upper part-legs in horizontal alinement and spaced part-legs in supporting relation to the table top.

2. A vertically adjustable table comprising a base member, a vertical post extending upwardly from said base member, spaced, lower part-legs upon the base member, a table top, a vertical element extending downwardly from said table top assembled with said vertical post for rotative and sliding movement, means precluding removal of said vertical post from said vertical ele-

ment, and spaced, upper part-legs extending downwardly from the table top, said lower and upper part-legs being situated in a circumference concentric with said vertical post and vertical element, there being a lower part-leg corresponding to each of said upper part-legs, and said table top being rotatably and slidably adjustable selectively to situate lower ends of said upper part-legs in engaged relation with upper ends of their corresponding lower part-legs or to situate corresponding lower and upper part-legs in horizontal alinement and spaced part-legs in supporting relation to the table top.

3. A vertically adjustable table comprising a base member, a vertical post extending upwardly from said base member, spaced, lower part-legs upon the base member, a table top, a vertical element extending downwardly from said table top assembled with said vertical post for rotative and sliding movement, resilient means counterbalancing the weight of said table top, means precluding removal of said vertical post from said vertical element, and spaced, upper part-legs extending downwardly from the table top, said lower and upper part-legs being situated in a circumference concentric with said vertical post and vertical element, there being a lower part-leg corresponding to each of said upper part-legs, and said table top being rotatably and slidably adjustable selectively to situate lower ends of said upper part-legs in engaged relation with upper ends of their corresponding lower part-legs or to situate corresponding lower and upper part-legs in horizontal alinement and spaced part-legs in supporting relation to the table top.

4. The combination as specified in claim 1, and means for precluding rotation of the table top relative to said base member both when the lower ends of said upper part-legs are engaged with the upper ends of said lower part-legs and spaced part-legs are in supporting relation to the table top.

5. A vertically adjustable table comprising a base member, a vertical hollow post upon said base member, spaced, lower part-legs upon the base member, a table top, a hollow tubular element extending vertically downward from said table top at the center thereof and assembled with said hollow post for rotative and sliding movement, a guide rod supported by said base member and extending upwardly through said hollow post and into said hollow tubular element in spaced relation to an internal surface thereof, means precluding withdrawal of said hollow tubular element from said hollow post, a compression coil spring for counterbalancing the weight of the table top seated between said base member and said table top, and spaced, upper part-legs extending downwardly from the table top, said lower and upper part-legs being situated in a circumference concentric with said hollow post and hollow tubular element, there being a lower part-leg corresponding to each of said upper part-legs and said table top being rotatably and slidably adjustable selectively to situate lower ends of said upper part-legs in engaged relation with upper ends of their corresponding lower part-legs or to situate corresponding lower and upper part-legs in horizontal alinement and spaced part-legs in supporting relation to the table top.
